UNITED STATES PATENT OFFICE.

THOMAS MASON, OF NEW YORK, N. Y.

SPOOL-STAND.

SPECIFICATION forming part of Letters Patent No. 605,254, dated June 7, 1898.

Application filed June 21, 1897. Serial No. 641,695. (No model.)

To all whom it may concern:

Be it known that I, THOMAS MASON, a citizen of the United States, residing at New York, in the county of New York and State of New York, have invented certain new and useful Improvements in Spool-Stands, of which the following is a full and complete specification, such as will enable those skilled in the art to which it appertains to make and use the same.

This invention relates to spool-stands; and the object thereof is to provide an improved device of this class which is particularly adapted for use by dressmakers, milliners, and others of this class, but which may also be employed wherever such articles are required, a further object being to provide a spool-stand from which the spools cannot accidentally be lost or detached and from which said spools cannot be removed intentionally or otherwise except by one who has full authority to remove them.

The invention is fully disclosed in the following specification, of which the accompanying drawings form a part, in which—

Figure 1 is a sectional side view of my improved spool-stand; Fig. 2, a plan view thereof, with part of the construction broken away; Fig. 3, a side view of a spring-arm which I employ, and Fig. 4 an edge view thereof.

In the drawings forming part of this specification the separate parts of my improvement are designated by the same numerals of reference in each of the views, and in the practice of my invention I provide a spool-stand which comprises a base 5, to which is secured a standard 6, which is provided at a predetermined height with a shoulder or projection 7. I also mount on the upper portion of the standard 6 a plate or disk 9, which is adapted to turn on the upper portion of said standard while resting on the shoulder or projection 7, and this plate or disk is preferably in the form of a spider or consists of a hub 10, spokes 11, and an annular rim 12, and secured to the upper portion of the annular rim 12 are a plurality of vertical pins 13, any desired number of which may be employed. I also connect with the upper end of the standard 6 a supplemental disk or plate which consists of a hub 15, spokes 16, and a rim 17, which is preferably provided at regular in-

tervals with holes or openings 18 to render said rim lighter.

The bottom disk or plate is held in place by 55 a collar 19, which is mounted on the upper portion of the standard 6 and by which said bottom disk or plate is held in connection with the shoulder or projection 7 and cannot move vertically on said standard, and one 60 side of the standard 6 below the bottom disk or plate is provided with a casing 20, in which is mounted a vertically-movable locking-pin 21, the upper end of which is adapted to enter a hole or opening 22, formed in the 65 bottom of the hub of the disk or plate 9, adjacent to the central opening through which the standard 6 passes, and said pin 21 is adapted to be raised or lowered by means of a key 23 or operated in any desired manner, 70 the only object in this connection being to provide a suitable lock whereby the bottom disk or plate 9 may be locked upon the standard 6 and cannot be turned thereon and whereby when the said lock is not in operation the said disk or plate 9 may be turned 75 as desired.

It will be observed that the outer rims 17 and 12 of the upper and lower disks or plates are in direct vertical line, and the rim 17 of 80 the upper disk or plate is provided at one side with a large opening 26, and in order to place the spools 24 in position the bottom disk or plate must be so turned that the pins 13 will come directly under the opening 26, and 85 it will be apparent that a spool may be placed on each of the pins 13 by turning said bottom disk or plate, and when each of the pins 13, or any desired number thereof, are provided with spools the bottom disk or plate 9 is turned 90 and locked in position, so that the spools cannot be removed from their respective pins. The upper disk or plate is placed at such a distance from the top of the pins 13 as to admit of the free rotation of the same, while 95 preventing the removal of the spools except by means of the openings 26, which will necessarily require the free rotation of the lower disk to bring the pins 13 successively in alignment with said opening to permit the removal 100 of each of the spools. I also secure to the rim of the bottom disk or plate 9 upwardly-directed spring-arms 27, which are provided at their upper ends with projections 28, which

overlap the ends of the spools, and said spring-arms are provided with transverse openings 29, and the thread from the spools is passed through said transverse openings, and said 5 spring-arms are secured to said disk or plate by means of angular extensions 30 at the lower ends thereof, through which screws 14 are passed. These spring-arms, however, are not absolutely essential to my invention, and 10 it will be observed that I have only shown two spools in position; but it will be apparent that each of the pins 13 is adapted to receive a spool.

Having fully described my invention, I 15 claim as new and desire to secure by Letters Patent—

1. In a spool-stand, the combination of a base, an upright standard, a revoluble plate mounted thereon, upwardly-directed pins 20 supported by said plate, an upper disk or plate mounted on said standard above said revoluble plate and having an opening through which spools of thread may be passed and means for locking said revoluble plate in position, said upper plate being in such relation to the top of said pins as to prevent the removal of a spool except through said opening therein, substantially as described.

2. A spool-stand provided with a vertical 25 standard having a shoulder formed thereon, a plate or disk revolubly mounted on said shoulder and standard having a socket therein adjacent to said standard, and provided

with vertical pins adapted to receive spools another disk or plate secured to the top of 35 said standard and provided with an opening through which the spools may be placed upon said standards, and a lock mounted in said shoulder and the bolt of which is adapted to enter the socket in said plate, substantially 40 as and for the purpose described.

3. A spool-stand provided with a vertical standard, a revoluble disk or plate mounted thereon, and provided with vertical pins which are adapted to receive spools, another disk 45 or plate secured to the top of said standard above said pins, and provided with an opening through which the spools may be inserted, and means for locking the lower disk or plate in position on said standard, the bottom disk 50 or plate being also provided with spring-arms, the upper ends of which overlap the ends of the spools, and said spring-arms being provided with holes or openings through which the thread is passed, said upper plate being 55 in such relation to the top of said pins as to prevent the removal of a spool, substantially as shown and described.

In testimony that I claim the foregoing as my invention I have signed my name, in presence of the subscribing witnesses, this 18th day of June, 1897.

THOMAS MASON.
